UNITED STATES PATENT OFFICE

137,657

DESIGN FOR A TOY DOLL

Frances Ruth Haedge, Dallas, Tex.

Application February 19, 1944, Serial No. 112,647

Term of patent 14 years

(Cl. D34—4)

To all whom it may concern:

Be it known that I, Frances Ruth Haedge, a citizen of the United States, residing at Dallas, in the county of Dallas and State of Texas, have invented a new, original, and ornamental Design for Toy Dolls, of which the following is a specification, reference being had to the accompanying drawing, forming part thereof.

I claim:

The ornamental design for a toy doll, as shown.

FRANCES RUTH HAEDGE.
